UNITED STATES PATENT OFFICE.

WILLIAM A. ANDREWS, OF DETROIT, MICHIGAN.

ELECTRIC LIQUID HEATER.

1,405,475.

Specification of Letters Patent. Patented Feb. 7, 1922.

Application filed March 11, 1920. Serial No. 365,107.

To all whom it may concern:

Be it known that I, WILLIAM A. ANDREWS, a citizen of the United States of America, residing at Detroit, in the county of Wayne 5 and State of Michigan, have invented certain new and useful Improvements in Electric Liquid Heaters, of which the following is a specification, reference being had therein to the accompanying drawings.

10 This invention relates to electric liquid heaters and relates more particularly to apparatus for electrically heating water.

15 It is the object of the invention to provide an apparatus for heating water and other liquids adapted to employ the liquid to be heated as a resistor element of the heater.

20 A further object is to provide a convenient adjusting means for regulating the amount of water functioning as a resistor in a heater of the above defined type.

In the drawings:

Figure 1 is a view in side elevation of the improved heater installed in a water tank or boiler;

25 Figure 2 is an end view of the electrodes of the heater and their mounting;

Figure 3 is a view similar to view 2 but showing a modified form of the invention.

In these views A and A' respectively 30 designate two rectangular insulating plates formed preferably of mica or porcelain, said plates being secured together at their corners by bolts B and being maintained in an accurately parallel spaced relation by 35 spacer sleeves C upon said bolts. Preferably, said plates are mounted vertically and are secured at their lower ends, respectively, to a pair of angle bars D. Upon the opposing faces of said plates there are mounted in

40 registering relation two copper plates E and E', a considerable margin being left between the peripheries of said plates and those of the insulating supporting plates A and A'. To said plates there are preferably respec- 45 tively connected the leads F and F' of any suitable energizing circuit. Between the plates E and E' there is arranged a pair of glass plates G and G' which are parallel to said plates E and E' and are adjustable to

50 and from each other, so as to occupy either an edgewise abutting relation or be spaced various distances apart. As a provision for relatively adjusting the plates G and G' preferably there are mounted upon the re- 55

with which are respectively engaged differentially threaded extremities of a rod I rotatable to effect a movement of the nuts H and attached plates G and G' to or from each other. As shown in Fig. 1 the de- 60 scribed liquid heater is mounted in a water tank J and the rod I passes through a wall of said tank and is journaled in a packed bearing K in said wall, gearing L being pro- 65 vided exteriorly of the tank for actuating said rod. Also in said figure the angle bars D are shown as having the vertical flanges at their end portions cut away and said end portions clamped between the flanges J' formed respectively upon the side 70 and bottom of the tank J.

In the operation of the described water heater when the circuit F, F', is energized the body of water intervening between the electrodes formed by the copper plates E 75 and E' acts as a heating resistor to complete the circuit, said water rising as its temper- 80 ature is raised and being replaced by colder water from the bottom portion of the tank. The effective resistance of the water gap 80 between electrodes E and E' is increased by adjusting the glass plates G and G' toward each other and when said plates are in contact the flow of current between the elec- 85 trodes is reduced to substantially zero. 85 When said glass plates are adjusted a maximum distance apart so as to be fully with- 90 drawn from between the electrodes E and E' the resistance of the water gap is mini- 90 mum. Thus, by properly adjusting said plates the resistance of the water gap may be so varied as to insure the desired heating effect.

In Figure 3 there is shown a somewhat modified form of the invention in which the resistance of the water gap is varied by in- 95 creasing or decreasing the distance between two parallel electrodes forming plates M and M', the same being adjustable by means of screws O and O', which screws serve to 100 conduct the current to said electrodes. By utilizing the liquid to be heated as the resistor element of the heater the invention accom- 105 plishes a considerable economy as com- 105 pared to the usual type of electric heaters providing a coil or other metallic element as a resistor.

What I claim as my invention is:

1. An electric liquid heater comprising a pair of electrodes formed by spaced parallel 110

plates, a pair of insulating plates arranged between said electrodes substantially in the same plane, and a common means for relatively shifting said insulator plates toward 5 and from each other to vary the water gap, intervening between said plates and between the two electrodes.

2. An electric liquid heater comprising a pair of electrodes formed by spaced parallel 10 plates, a pair of insulating plates respectively having portions projecting between said electrodes, nuts mounted upon said insulating plates and a screw having differentially threaded portions engaging said nuts 15 for adjusting said plates to vary the water gap formed between said plates and between the electrodes.

3. An electric liquid heater comprising a pair of electrodes adjustable with reference 20 to each other by means of a differentially threaded screw.

4. An electric liquid heater comprising a container, a pair of electrodes within said container adjustable with reference to each 25 other and means extending through the wall of said container operable from without for relatively shifting said electrodes.

5. An electric liquid heater comprising a container, a pair of electrodes formed by two 30 parallel spaced plates within said container, means for maintaining a predetermined spaced relation between said plates and means extending through the wall of said container for relatively shifting said plates

to vary the resistance of the water gap there- 35 between.

6. An electric liquid heater comprising a container, a pair of electrodes formed by spaced parallel plates within said container, a pair of insulating plates arranged between 40 said electrodes substantially in the same plane and means extending through the wall of said container for relatively shifting said insulator plates to vary the water gap intervening between said plates and between 45 the two electrodes.

7. An electric liquid heater comprising a container, a pair of electrodes formed by spaced parallel plates, a pair of insulating plates respectively having bars projecting 50 between said electrodes, nuts mounted upon said insulating plates and a screw having differentially threaded portions engaging said nuts for adjusting said plates to vary the water gap formed between said plates 55 and between the electrodes operable from the outside of said container.

8. An electric liquid heater comprising a pair of electrodes formed by spaced parallel plates, a pair of insulating plates arranged 60 between said electrodes substantially in the same plane, said plates extending beyond the periphery of said electrodes, and means for relatively shifting said insulating plates to vary the water gap intervening between 65 said plates and between the two electrodes.

In testimony whereof I affix my signature.
WILLIAM A. ANDREWS.
